UNITED STATES PATENT OFFICE

ALBERT H. KYLER, OF WESTMINSTER, MARYLAND

MACHINE FOR APPLYING LABELS TO CYLINDRICAL CANS OR THE LIKE

Application filed February 5, 1929. Serial No. 337,673.

This invention relates to improvements in machines for applying labels to cylindrical cans or the like.

More specifically, the invention pertains to improvements in labelling machines of the type in which the cans, while rolling along suitable tracks, pick up labels through the medium of an adhesive, and apply the labels as the cans travel along the tracks.

One of the objects of the invention is to provide novel means including a pump actuated by the travelling cans for depositing the adhesive in various amounts to the labels, and preferably to the trailing ends of the latter.

A further object is to furnish means of this character, including a novel valved perforated paste bar arranged to yieldingly engage the uppermost label of a stack for neatly applying adhesive to the labels.

Another object is to provide a machine of this type, including an elevator for the pile of labels; such elevator being moved step by step upwardly, by means actuated by the cans as they travel through the machine.

A still further object is to provide such a machine with a novel can actuated paste roll, so designed as to evenly apply spots of adhesive to the peripheries of the travelling cans, even though such peripheries should carry adhering foreign substances, such as parts of the substance which the cans contain.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is a perspective view of the machine, looking from one side thereof.

Fig. 2 is a similar view as seen from the opposite side.

Fig. 3 is a longitudinal vertical sectional view of the same.

Fig. 4 is a transverse sectional view on the line 4—4 of Fig. 3.

Fig. 5 is a similar view on the line 5—5 of Fig. 3.

Fig. 6 is a longitudinal horizontal sectional view of the machine.

Fig. 7 is a longitudinal vertical sectional view of the valved paste distributing bar.

Fig. 8 is an enlarged bottom plan view of the medial portion of the latter.

Fig. 9 is a vertical sectional view of the bar on line 9—9 of Fig. 8.

Fig. 10 is an elevation, partly in vertical section of the ratchet and pawl mechanism employed to drive the paste distributing pump, etc.

Fig. 11 is a developed perspective view of the parts of one of the rollers and bell-crank levers employed in driving certain parts by the cans as they roll over the tracks.

Fig. 12 is a vertical sectional view of the elevator operating means.

Fig. 13 is an elevation partly in section of means for actuating the elevator manually, and

Fig. 14 is an elevation of a fragment of the mechanism, shown in Fig. 13.

In the drawings, 11 indicates a table supported by legs 12. The table carries the frame 13 which supports certain parts of my improved mechanism.

Posts 14, at the ends of the frame, carry axles 15, 16 to which guide pulleys 17 are fixed. From Fig. 1, it will be observed that the shaft 16 has a projecting portion on which a driving gear 18 (Fig. 2) may be mounted for imparting movement to various movable parts of the machine. A rotary separator 19 is carried by brackets 20 on the feeding tracks 21, and this separator is driven by a belt 22 from a pulley 23 on the shaft 16. The separator is of conventional construction, and simply acts to space the cans as they roll one after the other in contacting relation down the tracks 21 on to the tracks

24 at the feeding end of the frame of the machine.

The cans are positively rolled through the machine by means of belts 25 which are mounted on the pulleys 17 and are pressed at their lower sides toward the table 12 by conventional pressure rollers 26, each of which is mounted on a pivoted arm 27, carried by a post 28; the roller on the arm being pressed downwardly, for example, by screws 29.

As each can is rolled along the tracks 24, its periphery is provided with series of spots of adhesive which extends lengthwise of the can. The means for accomplishing this are best shown in Figs. 3, 5 and 6. In these figures, a can 30 is shown in the act of rolling along the tracks 24, and its periphery is in contact with a positively driven paste roller 31, which is of special design. This roller is provided with spaced series of circumferential teeth 32, and the teeth of each series are separated by notches 33, so that when a line of these teeth extending lengthwise of the roller, comes in contact with the periphery of the can, a number of spots of adhesive will be deposited on the can. To this end, the paste roller is partially submerged in a paste pan or trough 34, which has apertured ears 35 engaging suspension screws 36. The pan is adjustably supported on these screws by thumb nuts 37, and this construction permits the pan to be raised or lowered.

The paste roller is fast on a shaft 38, journaled in brackets 39 in the pan, and having an extension 39' projecting through one end of the pan. This shaft is intermittently operated by a pawl and ratchet mechanism, actuated by the cans, as they travel along the tracks 24. Such pawl and ratchet mechanism may be of the type detailed in Figs. 10 and 11. For example, as shown in these figures, the shaft of the paste roll may be provided with a fixed ratchet wheel 40 that is engaged by a spring pressed pawl 41, pivotally mounted on a lever 42 which oscillates on the shaft. A link 43 connects this lever to one arm 44 of a bell-crank lever which is pivotally mounted on a post 45 that is carried by the frame, and positioned above one of the tracks 24. The other arm 46 of the bell crank carries a roller 47 which engages one of the belts 25. From this explanation it will be understood that as each can rolls along the tracks 24, it raises the roller 47, thus causing the bell-crank lever 44, 46 to depress the link 43, whereby the pawl 41 moves the ratchet wheel 40 one step and thereby rotates the paste roll one step. As the can moves from beneath the roller 47, the weight of the parts returns them to normal position, so that the pawl 41 may be properly positioned for the succeeding movement.

When the can or the like, with a line of paste spots applied thereto, reaches the end

48 of the tracks 24, (Fig. 3), it comes in contact with the uppermost label of a pile 49, carried by an elevator platform 50. This platform is shown in lowered position in full lines, and in upper position in dotted lines. It will be seen that the can, after leaving the tracks 24, rolls over the highest end of the uppermost label, and the parts are properly spaced so that the spots of glue on the can adhere to this label, and consequently, as the can rolls forwardly over intermediate tracks 51, the label is automatically wrapped around the can. At this point, it may be mentioned that the spots of paste on the can, supply the adhesive for one end of the label, and that a paste bar 52 applies adhesive to the other end of the label.

The tracks 51 are arranged at the medial portion of the frame, and their upper edges are of substantially arc-shape, as shown at 53, so that the can in rolling along the intermediate portion of the frame, is slightly elevated in order to permit the label to wrap around the same without interference. For this same purpose, the upper surface of the platform 50 is inclined downwardly toward the delivery end of the machine, whereby, while the can is rolling over the tracks 53, the label will wrap around the can until it reaches a point where it pulls the pasted trailing end of the label from beneath the paste bar 52. Of course, the belts 25 assist in wrapping the labels on the cans, and when the cans roll on to the delivery tracks 54, they are pressed against a pad 55, interposed between these tracks, and this causes the label to be smoothed out so that the can, in leaving the delivery end 56 of the tracks 54, will be properly labeled.

Reverting now to the medial portion of the machine, I desire to call particular attention to novel means which I have provided for applying a transverse line of paste spots to the upper surface of the trailing or lower end of the labels. Such means includes a pair of leaf springs 57, each of which is secured at its upper end to brackets or blocks 58, carried by the frame. These springs are arranged at opposite sides of the frame, and they curve rearwardly and downwardly to the paste bar 52 which they support. For the purpose of pressing this bar downwardly in contact with the labels carried by the elevator, screws 59 may be used. Each of these screws engages a stationary nut 60 on the frame, and its lower end impinges against the spring 57 with which it cooperates.

As best shown in Figs. 7 and 9, the paste bar 52 is formed of upper and lower flat strips 61 and 62, which are detachably connected together by any suitable means. Each strip has a semi-cylindrical longitudinally extending recess 64 to provide a cylindrical passageway lengthwise of the bar. Through this passageway, I extend a rotat-

able tube 65, having a series of apertures 66 which cooperate with ports 67 in the bar, to feed a multiplicity of streams of paste from the bar downwardly on to the labels on the elevator. A facing plate 68 that is secured to the under side of the bar by means of screws 69, is also provided with flared ports 70, which constantly register with the ports 67 to distribute the paste uniformly in spots across the face of each label. Grooves 71 extend from the ports 70 to one edge of the facing plate, and provide means for preventing the paste from spreading from the paste spots on the label, as the latter is withdrawn from beneath the bar.

The registering ports in the tube 65 and bar 52 provide means whereby the amount of paste fed to the ports 70 may be varied, and in order to permit the operator to turn the tube 65, the latter may be provided at one end with a finger wheel 72.

Fluid paste is continuously fed through the tube 65, and the quantity delivered therefrom to the labels is automatically controlled by the labels themselves, for the uppermost label of the pile will normally be closing the lower ends of the ports 70.

Paste is constantly fed through the bar from a reservoir 73, that is mounted in the frame, and provided with an outlet nipple 74, the latter being connected to the inlet of a suitable pump 75, which may be of the rotary gear type disclosed in the drawings. The delivery pipe 76 of this pump discharges into a flexible pipe 77 which carries the paste to the inlet end of the tube 65 of the paste bar. Any excess of paste over that delivered through the ports 70 is returned to the reservoir 73 by means of a flexible pipe 78 which leads from the outlet end of the tube 65 to the reservoir. The flexible pipes 77 and 78 permit the paste bar to rise and fall without interference.

At this point it might be noted that the lateral edges of the facing plate 68 of the paste bar diverge downwardly, as shown at 79, and they function in this way as guides or confining means for the lateral edges of the labels (see Fig. 7).

I prefer to operate the pump 75 by ratchet and pawl mechanism similar to that shown in Figs. 10 and 11. For example, the pump shaft 80 may have a fixed ratchet wheel 81, driven by a pawl 82, carried by a lever 83 that oscillates on the shaft. This lever (Fig. 3) is connected by a link 84 to a bell-crank lever 85 that is pivotally mounted at 86 on a bracket, carried by the frame. Each of the levers 83 and 85 is provided with a plurality of holes 83a to receive pins 83b which adjustably connect the link 84 to said levers. A roller 87 on the bell-crank lever, is pressed upwardly by each can, as the latter travels along the delivery tracks 54, and of course, this causes actuation of the pump in a man-

ner which will be apparent to those skilled in the art.

As before stated, the present invention includes novel elevating means. As best shown in Figs. 3 and 4, such means comprises a piston rod 88 that depends from the platform 50, into a cylinder 89, suspended from the table 11. The lower end of the rod 88 is provided with a piston 90 which is raised in the cylinder by placing pressure on a hydraulic fluid such as oil 91 which is forced into the lower end of the cylinder. For this purpose, the lower end of the cylinder communicates by a conduit 92, with the cylinder 93 of a reciprocating piston pump 94. This pump draws oil through a passageway 95 from a reservoir 96, and forces the same through the conduit 92 into the cylinder 89 for the purpose of elevating the platform 50. Of course, the pump 94 is provided with suitable valves, and its piston 97 is pivotally connected to an operating lever 98. The latter is pivotally mounted in the frame and is operatively connected to a link 99 which extends through a slot 100 in the table 11, and is joined at its upper end to a bell-crank lever 101. This lever is pivotally mounted on a bracket 102, and it carries a roller 103 that bears against one of the belts 25, whereby each time a can rolls beneath the roller 103, the latter will be raised to actuate the bell-crank lever 101, and this movement will be imparted by the link 99, to the pump lever 98, so that the pump 94 will raise the platform 50 step by step.

In mechanism of this character, it is desirable to have the platform 50 so combined with its elevating means that the platform may be immediately lowered whenever desired. I therefore place the interior of the cylinder 89 and reservoir 96 in communication, also by a passageway 104, which is normally closed by a hand operated valve 105. When this valve is opened, a spring 106, which has one of its ends connected to the platform 50, and its other end secured to the bottom of the reservoir, functions to pull the platform downwardly, and in such movement, the piston 90 forces the oil from the chamber 89 into the reservoir 96.

As it is also desirable that the platform 50 be raised to any required height rapidly, without actuating the same by means of the roller 103, I propose to combine the reservoir 96 with an additional pump 107, (see Figs. 13 and 14), which communicates by passageways 108 and 109 with the cylinder and reservoir. The piston 110 of this pump is provided with a yoke 111 at its upper end, which receives a stud 112 that is eccentrically arranged on a disk 113 that is rotatably mounted, and provided with a handle 114. When the handle is turned, the piston of this pump will be rapidly reciprocated, so that transfer of liquid from the reservoir 96 to the

cylinder 89 will be expedited, and the platform will be quickly raised.

It is believed that the operation may be readily understood from the foregoing description, but by way of reiteration, it may be stated that the cans coming from the sealing machine, will roll down the tracks 21, and will be properly spaced by the separator 19. Then, as each can rolls over the tracks 20 24, it will come in contact with the belts 25, and these belts will press the cans downwardly while they contact with the paste roller 31. Owing to the numerous notches and spaces in the periphery of this roller, spots of adhesive will be applied along a line lengthwise of the periphery of each can, and should any foreign substance, such as grains of corn, peas or the like be adhering to the surface of the can, and be transferred to the paste roller, the spaces and notches in the latter will receive such foreign substance, and prevent the same from interfering with the proper operation of the machine.

After the can has been provided with the paste spots, it continues to roll forward under the influence of the belts 25, and as the guide rollers which are engaging the belts above the tracks 24, are arranged on inclines, as shown in Fig. 5, the belts will only engage 25 the edges of the can, and consequently, the paste spots will not be disturbed.

Immediately the can leaves the tracks 24, its paste spots will adhere to the uppermost label of the pile 49, and as the can continues to move 30 forwardly over the medial tracks 53, under the influence of the belts 25, it will automatically wrap the label to which it is adhering, around itself, and just before leaving the tracks 53, it will pull the trailing end of the label from beneath the resiliently supported paste bar 52, and the trailing end of the label 35 will have a line of paste spots which it has received from said bar. Consequently, as the can rolls on to the pad 55, the label will be caused to adhere to the can, and will be 40 smoothed out before the can is delivered at the end 56 of the tracks 54.

Of course, as each can travels through the machine, it will actuate the described mechanism for causing intermittent movement of the paste roller 31, the pump 75, and the elevator 50.

From the foregoing, it is believed that the construction, operation and advantages of the invention may be readily understood, and I am aware that various changes may be made in the details disclosed, without departing from the spirit of the invention, as expressed in the claims.

60 What I claim and desire to secure by Letters Patent is:

1. In a machine for applying labels to cans or the like, means for supporting a label, a paste distributor adapted to apply paste to the label, and means for causing the paste to

move in an endless stream relatively to said distributor.

2. In a machine for applying labels to cans or the like, a label support, a paste distributor for applying paste to a label carried by the support, means for moving fluid paste in an endless stream through said distributor, and means for varying the amount of paste delivered by the distributor to the label.

3. In a machine for applying labels to cans or the like, a paste distributor including a bar having a passageway and provided at one side with a paste outlet means, a facing plate secured to the bar and having paste outlet means cooperating with the paste outlet means of the bar, said facing plate having outwardly diverging edge portions for guiding labels into position against the facing plate, and means for feeding fluid paste into said passageway.

4. In a machine for applying labels to cans or the like, a label support, a paste distributor adapted to apply paste to a label while the latter rests on the support, said distributor including a housing provided with paste outlet means, a paste reservoir, means for feeding paste from the reservoir into the housing, and means for returning excess paste from the housing to the reservoir.

5. In a machine for applying labels to cans or the like, a label support, a paste distributing bar extending across the support and adapted to apply paste to a label carried by the support, said bar having a passageway extending therethrough, and delivery ports communicating with the passageway, a rotatable tube extending through said passageway and having apertures cooperating with the ports for delivering the paste, a supply reservoir, means for feeding paste from the reservoir to the tube, and means for returning paste from the tube to the reservoir.

6. In a machine for applying labels to cans or the like, a label support, and means for distributing paste on to a label carried by said support, said means including a plate having a series of delivery ports and grooves communicating with said ports.

7. In a machine for applying labels to cans or the like, a label support, a paste distributing bar arranged to apply paste to a label carried by the support, resilient means for supporting said bar, and means for furnishing paste to said bar.

8. In mechanism as claimed in claim 7, means for adjusting the bar toward or away from the label support.

9. In a machine for applying labels to cans or the like, a label support, a paste distributor cooperating therewith for applying paste to a label while it is carried by said support, means including a pump for delivering paste to said paste distributor, a can runway, a member projecting into the path of movement of cans travelling along the runway, and

means including ratchet and pawl mechanism for operating the pump by said member.

10. In a machine of the character described, a runway for articles to be labeled, a label elevator, hydraulic means for actuating the elevator, and operating means for the elevator, including a part projecting into the path of movement of the articles, whereby movement of the articles along the runway will cause the elevator to actuate.

11. In a machine for applying labels to cans or the like, a label support, and a paste distributor adapted to apply paste to a label carried by the support, said distributor including a flat casing formed of upper and lower plates, each plate being grooved and the grooves forming a bore, the lower one of the plates being provided with spaced apertures communicating with said bore, a tube movably mounted in said bore and having paste outlet means cooperating with said apertures, and means for delivering paste to said tube.

12. In a machine for applying labels to cans or the like, a label elevator including a platform, a piston operatively connected to the platform, a cylinder for the piston, a reservoir for a liquid, means for pumping liquid from the reservoir into the cylinder, and manu-motive pumping means also cooperating with the reservoir and cylinder to permit the operator to rapidly pump liquid from the reservoir into the cylinder for expediting the raising of the platform.

13. In a machine for applying labels to cans or the like, a label elevator including a platform, a piston operatively connected to the platform, a cylinder for the piston, a reservoir for a liquid, means for pumping liquid from the reservoir into the cylinder, and valve controlled means to permit liquid to flow from the cylinder into the reservoir when the platform is to be lowered.

In testimony whereof I have signed this specification.

45. ALBERT H. KYLER.
